No. 742.

Leibbrandt, McDowell & Co.
Assignees of
Garrison Smith and Henry Brown.
Design for a Coal Stove.

Patented Nov. 6, 1855.

Garrison, Smith & Henry Brown, of Philadelphia Pa.

Assignors to

Leibrandt, McDowell & Co. of Philadelphia,

Letters Patent No. 742. Dated Nov. 6. 1855.

The Schedule referred to in these Letters Patent and making part of the same.

To all whom it may concern,

Be it known, That Mr. Garrison, Smith, and Henry Brown, of the city and county of Philadelphia, and State of Pennsylvania have invented or produced a new and original design for a coal stove which we call the "Egg Cylinder"; and we do hereby declare the following to be a full, clear and exact description of the same, reference being had to the accompanying drawings, which represent a perspective view of the base or lower part of the stove, and the cylinder connected therewith, and forming a part of this description. A, represents the bottom plate, the hearth portion B, of which is bell shaped, with indented edges, and ornamented all around with semi-ovates a, a, b, and scrolls b. The plate A is supported on legs C, margined with volutes c and diamond ground work d.

D, is the draft and register plate fitting into openings or recesses formed in the base or bottom plate and also in the bell shaped cylinder E, which rests upon the bottom plate. The cylinder E is ornamented with elongated ovates e, with a sunken center f. Upon the bell shaped cylinder E rests the egg shaped cylinder F, formed of two segments, uniting at their bases, and furnished with flutings g.

G, is the handle for shaking the grate.

Having thus fully described the nature of our invention, what we claim therein as new, and desire to secure by letters patent is the combination of ornaments herein set forth, the whole forming an original design for a coal stove.
